Primary Examiner — Angela J Lee*(74) Attorney, Agent, or Firm* — Jianq Chyun IP Office**CLAIM**

The ornamental design for a display screen with graphical user interface, as shown and described.

DESCRIPTION

The single FIGURE is a front view of a display screen with graphical user interface showing our new design.

The broken line showing of portions of the graphic user interface and the broken line showing of the display screen illustrate unclaimed environment and form no part of the claimed design.

1 Claim, 1 Drawing Sheet
